CAGE

Filed Feb. 28, 1929

UNITED STATES PATENT OFFICE

CHARLES H. HENNINGS, OF CHICAGO, ILLINOIS, ASSIGNOR TO HENNINGS MANUFACTURING CO., A CORPORATION OF ILLINOIS

CAGE

Application filed February 28, 1929. Serial No. 343,258.

This invention relates to improvements in cages of the type having a body portion of strands, wires, bars or the like, and more particularly to the body construction of such cages, the invention set forth hereinafter being highly desirable in connection with bird cages and the like, although the invention may have other and varied uses as will be apparent to one skilled in the art.

10 In the art of cage making, especially bird cages, it is desirable to provide as simple and inexpensive a construction as possible without detracting from the quality and appearance of the finished article. In attaining this end, ease and simplicity in assembling the parts making up the cage body play an important part. In the past, cages of this character have in most instances proven objectionably costly in body construction. 15 In some instances these heretofore known cages necessitated the securement of transverse bands to the strands outlining the cage body by means of soldering, brazing, welding, and the like, and such a process is more than desirably laborious and expensive, notwithstanding the fact that the resulting cage to a material extent lacked durability. In other instances bands were secured to the strands by first inserting the strands endwise through means associated with the bands, and such an assembly is obviously objectionably laborious and tedious.

35 The present invention has been designed to overcome the above noted as well as other defects and objections in the provision of a cage incorporating a body defined by spaced strands to which reinforcing bands are attached in a simple, expeditious manner with no soldering, brazing or the like 40 or any endwise insertion of the strands.

The invention also seeks the provision of a cage incorporating a novel body construction which is extremely simple to assemble and provides more than sufficient rigidity and 45 durability to the cage body.

Another object of the present invention is to provide a cage body defined by spaced strands reinforced by transverse bands with the engagement between the bands and

strands effectively concealed by means enhancing the appearance of the cage.

Still another object of the present invention is the provision of an improved reinforcing band for cages incorporating a plurality of spaced strands in the body thereof.

While some of the more salient features, characteristics, and advantages of a device embodying this invention have been above pointed out, others will become apparent 55 from the following disclosures.

60 The invention includes these and other features of construction and combinations of parts hereinafter described, and shown in a preferred form in the drawing, as more particularly indicated by the claim.

65 On the drawing:

Figure 1 is a view in elevation of a device embodying principles of the present invention.

70 Figure 2 is an enlarged fragmentary elevational view of a portion of the body of the device shown in Figure 1, the view being taken from the interior of the body portion.

75 Figure 3 is an enlarged fragmentary view showing the exterior of one of the bands shown in Figure 2.

80 Figure 4 is a fragmentary plan sectional view taken substantially as indicated by the line IV—IV of Figure 3, showing the structure in a premature stage of assembly.

85 Figure 5 is a view similar to Figure 4, showing the structure at the final stage of assembly.

Figure 6 is an enlarged fragmentary view 90 of a portion of the structure shown in Figure 1.

Figure 7 is a vertical sectional view taken substantially as indicated by line VII—VII of Figure 6, with parts omitted.

95 Figure 8 is a fragmentary view in elevation, with parts omitted, showing a different portion of the structure disclosed in Figure 6.

Figure 9 is a bottom plan sectional view taken substantially as indicated by the line IX—IX of Figure 8.

As shown on the drawing:

In the structure selected for illustrating an embodiment of the present invention, there is shown a bird cage including a base 100

10 having a drawer 11 therein, upon which base portion a body 12 is mounted, there being a top decorative element 13 on the body 12 and a hanger 14 for the cage projecting through the element 13.

5 Although the body 12, in the present instance, is shown associated with a base substantially the same as that disclosed and described in my copending application for Letters Patent for "cage", Serial No. 343,257, filed February 28, 1929, and with a top construction substantially similar to that set forth in my copending application for "cage" Serial No. 343,259, filed February 28, 1929, it is to be understood that the body 12 may be associated with any suitable base and top construction.

20 The cage body 12 is defined by a plurality of spaced strands 15, preferably resilient and of wire, which are held in their proper positions by means of transverse reinforcing bands 16, there being a screen 17 disposed about the strands 15 between the two lowermost reinforcing bands 16 to prevent the scattering of food particles and débris by the animal occupant of the cage. As seen more clearly in Figure 2, certain of the strands 15 are outwardly bent as at 18 and 19 to provide a greater space therebetween for the entrance and retention of a lug 20 on the customary food or water receptacle 21.

25 In the present instance the reinforcing bands 16 are shown as embracing exterior portions of the strands 15, but it is obvious that if so desired the bands 16 may be disposed on the inner side of the strands. Each of the bands 16 is in the form of a strip having tongues 22 struck therefrom at spaced intervals therealong, there being a pair of 30 tongues 22 for each of the strands 15. As seen more clearly in Figure 4 a strand 15 is disposed between a pair of tongues 22, the tongues then being bent into engagement with the strand as seen more clearly in Figure 5. Each of the strands 15 is firmly gripped by a pair of tongues 22 so that all relative movement between the strands and reinforcing bands is eliminated, the comparatively sharp edges of the tongues pressing against 35 the strands as indicated at 23 aiding in preventing a slipping movement between the bands and strands.

40 In the above manner a rigid and firm cage body is provided, it being only necessary to secure the strands 15 adjacent the top of the cage, apply the reinforcing bands 16 thereon, and by any desirable means or process bend the tongues 22 into contact with the strands 15.

45 To enhance the appearance of the cage as a whole external decorative bands 24 having beads 25 or any desired configuration formed thereon are engaged around the reinforcing bands 16. The decorative bands 24 effectively conceal the apertures left in the bands 16

when the tongues 22 are formed and also the engagement of the bands 16 with the strands 15. To aid in holding the decorative bands 24 in proper position each of them is provided with a flange 26 to engage the top 70 of the bands 16, as seen more clearly in Figure 7. Each of the external bands 24 is preferably resilient and has one end thereof slightly offset as indicated at 27 (Figure 9), from which offset portion a lug 28 is struck 75 which extends through a suitable aperture in the other end of the band 24 and engages the outside thereof, whereby the decorative band is adequately secured around one of the reinforcing bands 16.

80 As seen in Figure 1, certain of the strands 15 are twice severed and the ends of the severed portions are held by strips 29 similar in construction to the reinforcing bands 16, whereby a cage door 30 is formed. A shorter section of a band 16 provides a handle 31 for the door. Of course, the strips 29 and section 31 are preferably enclosed by decorative elements akin to the bands 24.

85 From the foregoing it will be apparent that I have provided a cage incorporating a body defined by a plurality of spaced strands with reinforcing means secured to the strands in a simple, expeditious manner, and wherein the engagement between the reinforcing bands and the individual strands is effectively concealed by means of enhancing the external appearance of the cage. Moreover, although the cage body hereinabove described 90 may be very easily assembled, it nevertheless is extremely rigid and durable, and may be economically manufactured.

95 I am aware that many changes may be made and numerous details of construction 100 may be varied through a wide range without departing from the principles of this invention, and I therefore do not purpose limiting the patent granted hereon otherwise than necessitated by the prior art.

105 I claim as my invention:

110 In a bird cage, spaced wires shaped to define the cage body, means including reinforcing bands for holding said wires in their proper positions, and a decorative band for each of said reinforcing bands and having a slot in one end thereof and an offset tongue on the other end thereof extending in the same direction as said last said end and engageable in said slot, and an inwardly extending flange on each of said decorative bands for 115 engagement over an edge of the respective reinforcing band to aid said tongue and slot connection in holding said decorative band on said reinforcing band.

120 In testimony whereof I have hereunto subscribed my name at Chicago, Cook County, Illinois.

CHARLES H. HENNINGS.
